BOTTLE

John R. Osborn, New York, N.Y., assignor to National Distillers and Chemical Corporation, New York, N.Y.

Filed June 28, 1971, Ser. No. 157,809

Term of patent 14 years

Int. Cl. D9—01

U.S. Cl. D9—44

FIG. 4

FIG. 1

FIG. 2

FIG. 3

FIG. 6

FIG. 5

FIG. 1 is a front elevational view of a bottle showing my new design;

FIG. 2 is a side elevational view thereof, the opposite side of the bottle being the same in appearance as the side shown;

FIG. 3 is a rear elevational view thereof;

FIG. 4 is a top plan view thereof;

FIG. 5 is a bottom plan view thereof; and

FIG. 6 is a horizontal sectional view taken on the line 6—6 of FIG. 1.

I claim:

The ornamental design for a bottle, as shown and described.
